CLAIM

The ornamental design for a foot support for weightlifting bench, as shown.

DESCRIPTION

FIG. 1 depicts a perspective view of an environment for a foot support for weightlifting bench.

FIG. 2 depicts an enlarged perspective view of the environment for the foot support for weightlifting bench of FIG. 1. FIG. 3 is a top perspective view of an embodiment of the foot support for weightlifting bench.

FIG. 4 is a bottom perspective view of the foot support for weightlifting bench of FIG. 3.

FIG. 5 is a front elevation view of the foot support for weightlifting bench of FIG. 3.

FIG. 6 is a rear elevation view of the foot support for weightlifting bench of FIG. 3.

FIG. 7 is a right side elevation view of the foot support for weightlifting bench of FIG. 3.

FIG. 8 is a left side elevation view of the foot support for weightlifting bench of FIG. 3.

FIG. 9 is a top plan view of the foot support for weightlifting bench of FIG. 3; and,

FIG. 10 is a bottom plan view of the foot support for weightlifting bench of FIG. 3.

The broken lines depict an environment for or portions of the foot support for weightlifting bench and form no part of the claimed design.
